Primary Examiner — Karen E Kearney

(74) Attorney, Agent, or Firm — Banner & Witcoff, Ltd.

CLAIM

(57) The ornamental design for a display screen with a position indicator icon, as shown and described.

DESCRIPTION

FIG. 1 is a front view of a display screen with a position indicator icon showing the new design; and, FIG. 2 is a front view of an alternative embodiment of a display screen with a position indicator icon showing the design. The broken line showing of the display screen is for environmental purposes only and forms no part of the claimed design.

1 Claim, 2 Drawing Sheets
